UNITED STATES PATENT OFFICE.

THOMAS S. WILES, OF ALBANY, AND FREDERIC W. BROWN, OF TROY,
NEW YORK.

STAND-PIPE.

SPECIFICATION forming part of Letters Patent No. 424,395, dated March 25, 1890.

Application filed December 24, 1887. Serial No. 258,923. (No model.)

To all whom it may concern:

Be it known that we, THOMAS S. WILES and FREDERIC W. BROWN, citizens of the United States, residing at Albany and Troy, respectively, in the counties of Albany and Rensselaer, State of New York, have invented certain new and useful Improvements in Stand-Pipes, of which the following is a specification, reference being had therein to the accompanying drawings.

This invention relates to portable water-towers or stand-pipes used by fire departments to discharge water from an elevation upon a fire in a high building.

Water-towers have heretofore been made in a telescopic form. In this invention, however, the tower is so constructed as to be raised from a horizontal to a vertical position and extended to any desired height by means of hydraulic pressure. It is also provided with means for delivering the stream of water from the nozzle at the top of the tower in any desired direction.

In large cities buildings are now carried to a great height, and the streets are often narrow and usually encumbered with wires and other obstructions, and it is therefore difficult for the fire department to reach a fire in the upper stories of a high building or to make adequate efforts to extinguish it. To meet this want devices of various kinds have been conceived to avoid the danger and delay in carrying up hose on ladders in the old manner. Some of the machines suggested have had other objects in view in connection with the water service—such as saving life and goods and enabling firemen to gain access to high buildings, &c.—and others have been made simply for the delivery of a stream of water. Our invention pertains to a machine of the latter class, and is simple, automatic, and speedy in its operation.

On account of the weight of the column of water in the tower and of the strain produced by that weight and the pressure necessarily employed to throw the water to the distance required the apparatus must be strong in construction, firm on base, and not too heavy to be easily transported.

Other objects and advantages of the invention will be hereinafter described, and the

novel features thereof particularly pointed out in the claims.

Referring to the drawings, Figure 1 is a perspective of the entire apparatus, the stand-pipe being closed and in a horizontal position. Fig. 2 is a front elevation showing the lowest and next to the lowest sections of the stand-pipe telescopically extended and in a vertical position. Fig. 3 is a rear elevation, the stand-pipe being in the position shown in Fig. 1. Figs. 4 to 9 are details of the adjustable locking mechanism for retaining the stand-pipe in a vertical or other desired position. Figs. 10 to 16 are details showing the construction of the truck body or platform. Fig. 17 is a front elevation, with parts in section, of the upper end of the stand-pipe. Fig. 17^a is a longitudinal section of the pipe adjacent to the nozzle, the nozzle-controlling devices being mounted thereon. Fig. 17^b is a detail in transverse section on line $\alpha\alpha$ of Fig. 17. Fig. 18 is a central transverse section of the joint employed in connecting two sections of the stand-pipe. Fig. 19 is a side elevation of the same with the clamping devices and the connections of the nozzle-rotating shafts. Fig. 19^a is a preferred form of connecting the sections of the pipe-connecting sleeve. Figs. 20, 21, and 22 are details of mechanism employed in locking and unlocking the braces of the stand-pipe-lifting cylinders. Figs. 23 to 26 are plans of the various yokes employed. Fig. 27 is a front elevation of the case for the valve mechanism employed at the butt of the stand-pipe. Fig. 28 is a front elevation, and Fig. 29 an end elevation, of the gate employed in the case shown in Fig. 27. Fig. 30 is a plan and partial section of the butt of the pipe and the valve mechanism therein. Fig. 31 is a central vertical section of Fig. 30; and Fig. 32 is a similar section to that of Fig. 31, the cut-off being shown in its lowest position. Figs. 33 to 36 are details of the check-valve employed at the butt of the stand-pipe. Figs. 37 to 41 are details of the gear-inclosing case employed. Figs. 42 to 45 are respectively plans and vertical sections of the nozzle-rotating gear and the cap for the same.

Similar letters of reference indicate similar parts in all the figures of the drawings.

A represents the truck, suitably mounted

upon wheels and having its sills or side rails formed, as clearly shown in Figs. 10 to 16, of channel-irons A' A^2 A^3 A^4 and of plates A^5 , secured to the edges thereof by suitable bolts 5 or rivets. The channel-iron A^4 extends from end to end of the sills, while at the upper edge the irons A' A^2 are placed a slight distance below the upper edge of the plates A^5 , so as to form the grooves extending from the 10 end toward the middle of each sill. The channel-iron A^4 is divided at middle of sill to admit the cylinder. The channel-iron A^3 is laid flush with the top of the sill along the middle portion thereof, and is bent down- 15 wardly, as at A^{3x} , to form a recess for the reception of the foot of a brace employed in connection with the stand-pipe-elevating cylinder. The disposition of the channel-irons in the upper edge of the sill will be clearly 20 understood by reference to Fig. 14, which is a section of Fig. 12 on the line 1, Fig. 15, which is a section on the line 2, and Fig. 16, which is a section on the line 3 of said figure. At about middle length of each sill the plates 25 and irons thereof are shaped to form pockets A^6 for the reception of the stand-pipe-elevating cylinders. Re-enforcing bands A^7 may be arranged on the outside of the plates to embrace the pockets in order to strengthen 30 the same. Adjacent to the cylinder-pockets a cross-beam A^8 is arranged, having its front edge set back. Any suitable platform, as A^9 , is arranged in rear of the cylinder-pockets, and any suitable bracing, as A^{10} , is arranged 35 at the front of the truck, which is thus provided with a platform at the rear end and opening at the front, through which opening, as will hereinafter appear, the stand-pipe proper passes when being brought to a vertical 40 position.

B represents the lower or fixed section of the stand-pipe-elevating cylinders, and these are arranged in the pockets A^6 , so as to be rigidly held therein, and are strengthened by 45 a suitable system of truss-rods extending from each cylinder to the sill of the truck in which it is mounted. Truss-straps B' extend from the upper end of the sill or from a collar affixed thereto. Similar truss-straps extend 50 from the lower edge of the sill to a band B^2 , secured about the cylinder below the sill and connected with the casting forming the lower end of the cylinder by rods B^3 , which assist in preventing the collar B^2 from being drawn 55 upwardly along the cylinder. Truss-rods B^4 extend from the bottom of the cylinder to the lower edge of the sill at points farther from the center of the sill than do the straps B' .

C represents the movable section of the telescopic cylinders employed for raising the stand-pipe proper. From the upper end of the said section C , or from a collar or head mounted thereon, are braces B^5 B^6 , the former extending rearwardly and the latter forwardly and riding upon the upper edge of the sills, the feet B^{5x} sliding in the grooves formed by arranging the channel-irons A' A^2

below the edges of the plates A^5 , as hereinbefore described.

On the inner sides of the opposite sills of the platform are arranged a pair of rack-bars G . A cross-shaft G' , having a handle G^2 , arranged on the outside of one of the sills, is provided with a pinion G^3 , adapted to mesh with the oppositely-arranged rack-bars. Between the plates A^5 of each sill and at each of the recesses formed by the bends A^{3x} in the irons A' A^2 are arranged sliding bars or bolts G^4 , the function of each of which is to close the recesses and to form a track on the same level with the bars A^2 when the sliding bars or bolts are thrown into said recesses, as shown in Fig. 22, so as to facilitate the lowering of the movable sections of the stand-pipe-elevating cylinders. The function of the rack-bars is to withdraw the bolts or bars G^4 from the recesses in order that the latter may serve to lock or retain the feet of the braces from spreading when the sections of the cylinder are elevated. The upper rack-bar G is connected by a pin, bolt, or arm G^5 to the front bar or bolt G^4 , and the lower rack-bar G is bent, as at G^6 , to pass the cylinder-pocket A^6 , and is then bent upwardly and connected, as at G^7 , with the opposite bar G^4 by a pin or bolt similar to the bolt G^5 , the bolts passing through slots G^8 , formed in the plates A^5 . The connections of the rack-bars at either side of the truck-body are the same, and, there being a pinion on the shaft G' for each pair of rack-bars, it will be seen that by means of the handle G^2 all of the sliding bars may be simultaneously operated.

Instead of forming the recesses in a groove by bending the plates, as at A^{3x} , the feet B^{5x} may be made to embrace the upper edge of the rails or sills and notches or recesses formed therein. At their lower ends the cylinders B are connected by a curved pipe B^7 , (see Fig. 6,) having connected therewith a T branch B^8 , provided with valves B^{8x} and bibs B^9 , to which a hose may be connected for supplying water to the cylinders B . Now it will be seen that when the water is let into the cylinders B the movable section thereof will be raised, and the braces B^5 B^6 will travel from the ends toward the middle of the sills until they reach the recesses formed at the bends A^{3x} of the channel-irons, when the feet of the braces will drop into the recesses thus formed and abut against the inner ends of the outer sections A' A^2 of the channel-irons, and thus serve to maintain the cylinders C in an extended position, and also materially lessen the load which said cylinders are required to support.

In order to maintain the feet of the braces within the grooves in the top of the sills and to regulate the movement of the same, so as to render it uniform, and to provide a limit to said movement, a rod B^{10} extends from the collar B^2 on each of the cylinders B upwardly and serves as a guide for a block B^{11} , mounted thereon. From the said block there extend

from each of the braces B^5 B^6 truss-rods B^{12} , and these rods, the sliding block, and the rod B^{10} , with the upper and lower collars B^2 , serve the purposes and functions just mentioned.

5 A side brace B^{13} is pivotally connected with the cylinders, either at the top of the cylinder B , as shown in Fig. 1, or at the top of the movable cylinder C , as shown in Fig. 2, for the purpose of being swung out to a position 10 at the side of the machine and embracing it laterally. The detailed construction of the brace B^{13} is shown in Fig. 2^a, it having a socketed interiorly-screw-threaded eye B^{14} , which is connected with a hook or bolt or other suitable lock formed on the collar or cap-piece of 15 the section with which it is employed. The rod also has rigid arms B^{15} for the purpose of turning the same, so that the screw-threaded ends thereof may be rotated in the eye-socket 20 and in the socket B^{16} , which is pointed for the purpose of giving firm hold in the earth or other foundation. Now it will be seen that a firm bracing of the machine laterally can be secured by means of the brace-rods just described, and either before or after the lifting-cylinders are extended. When not in use as 25 braces, the rods B^{13} may be supported in any suitable manner on the truck—as, for example, by a hook B^{17} , Fig. 1.

30 C' is a cross-beam extending from the top of one of the sections C to the other and curved to the front—that is, opposite to the curvature of the cross-beam A^8 of the platform. From this beam there depend hangers 35 C^2 , which terminate in bearings for the trunnions C^3 of a gimbal-ring C^4 on the pivots C^5 , upon which is supported the lower section of the stand-pipe proper. Now it will be seen that by reason of the gimbal-support of the stand-pipe 40 and of the forward curvature of the cross-beam C' , the rear offsetting of the cross-beam A^8 of the truck-frame, and the open rear portion of the truck-frame, as the cylinders B or their movable sections C are extended by the admission 45 of water, as described, the stand-pipe proper can swing from a horizontal to a vertical position. Now, in order to control or in a measure direct the stand-pipe in its movements from a horizontal to a vertical position, or the reverse, so as to bring its butt 50 and top to a substantially common horizontal plane, there is pivotally connected with the lower section of the stand-pipe a lever C^6 , (see Fig. 1,) which is adapted to be secured 55 at its free end under a hook C^7 , also secured to the lower section of the stand-pipe. The shape of this lever is such that in going with the stand-pipe through the movements described it comes into contact with the rollers 60 C^8 , mounted on the brace B^6 , and these parts act to guide or control the butt of the stand-pipe in said movement. Cross-bar C' moves, when elevated and lowered, in a vertical plane. In the same vertical plane the gimbal-support mechanism of the stand-pipe is 65 pivoted. The upper end of the brace B^6 is also pivoted in the same vertical plane, while

its lower ends travel in a horizontal plane—viz., along the upper edges of the side rails—so that an intermediate point on the brace— 70 as, for example, at the roller C^8 —takes a resultant course, which is curvilinear, or a combined upward and rearward movement. The lever C^8 confines the lower part of the stand-pipe in such a manner as to cause it to follow the brace in said movement, instead of permitting it to swing freely and uncontrolled from a horizontal to a vertical position. The lever need not be necessarily curved, although it is preferably so, to reduce to a minimum 80 the friction of the moving parts upon each other. If the lever is discarded, the lower part of the stand-pipe is left free to accumulate a momentum in cases where the cylinders B are suddenly extended in the act of 85 erecting the stand-pipe. This is prevented by the use of a lever or guiding-bar or connection of any description between the brace and the stand-pipe.

An arm C^9 , Figs. 1 and 3, serves the simple 90 purpose of supporting the top portion of the stand-pipe when in a horizontal position upon the truck. This arm may project either from the stand-pipe or from the truck.

By reference to Fig. 2 it will be seen that 95 the brace B^6 is composed of a truss framework, and that it terminates in two legs, which, as more clearly shown in Fig. 1, have the feet B^{5x} for riding along the sills. The trussing of this brace renders it strong, and the construction of the leg portions without any cross-trussing adapts the brace as a whole to bestride the stand-pipe when in a horizontal position, and thus co-operates with the curvature of the cross-beams and open portion of 100 the platform of the truck in permitting of the stand-pipe to be changed from a horizontal to the vertical position, and the reverse. The braces B^5 are, however, separately constructed, and each is in the form of a ladder, thus providing means for access to a platform C^{10} , secured to the stand-pipe so as to occupy a position above the cross-beam C' when the pipe is elevated. The platform is for the purpose 105 of giving the operator access to the various 110 clamps and valve-controlling devices, herein-after described. When the pipe is elevated, as shown in Fig. 2, adjustable guy-bolts D are brought into operation for the purpose of securing the pipe against accidental displacement from a vertical or angular position. When extended to a great distance and properly braced, this apparatus is so constructed 115 that the pipe may, if desired, and if circumstances require it, be inclined more or less from a true perpendicular; but in practical 120 operation the nearer to a true perpendicular the stand-pipe is brought the more stable it is. The guy-bolts D are connected at one end with the curved pipe or with brackets D' , 125 mounted on or secured thereto. In these brackets are mounted pins or bolts D^3 , held from upward displacement by a key or pin D^4 , passing through the bolt below the bracket.

The upper end of the pin or bolt D³ is bifurcated, and has pivoted in the bifurcations a nut D⁵, adapted to fit the bolt D. A hand-wheel or other bolt-operating device D⁶ is mounted upon the bolt D, and the latter terminates in a spherical head D⁷.

To the stand-pipe and near its butt are secured casings D⁸, in which are two rigid seats D⁹, one arranged below and the other above 10 the head D⁷ of the bolt when inserted therein. Each of the cases is provided with an oblong slot D^{8x}, which is sufficient for the entrance of the head D⁷ of the bolt. Within the casing is a cylinder D¹⁰, having a slot D^{10x}, adapted 15 to embrace the bolt adjacent to its head. The cylinder D¹⁰ is by a pin D¹¹ connected to a rod D¹², passing through the cap D¹³, which is screw-threaded upon the case. The upper seat D^{9*} is bored longitudinally for the rod 20 D¹² and slotted transversely, as at D^{12x}, for the passage of the pin D¹¹ therethrough, so that the cylinder may be raised and lowered within the case to permit of the insertion and withdrawal of the head of the bolt therefrom 25 and to maintain the bolt therein by passing the cylinder so that the slot D^{10x} embraces the bolt adjacent to the head. Now, when the proper connections are made at each end of the bolt D by turning the hand-wheel D⁶, the 30 butt of the stand-pipe may be moved in different directions with relation to the curved pipe with which it is connected, and thus the stand-pipe may be disposed perpendicularly or at an angle, as desired.

35 The stand-pipe proper is composed of a series of pipes fitted to each other telescopically, the lower section E being the largest and adapted to receive the upper section E³ and the intermediate sections E' E². Any desired 40 number of sections may be used.

Referring to Figs. 18 and 19, the construction of the joints or couplings of the sections comprises a casting E⁴, interiorly screw-threaded for connection with a lower section 45 of a pair. The casting also has an inner annular flange E⁵, which serves a double function—that of a seat for suitable packing E⁶ and as an abutment for a coiled or other spring E⁷, arranged between the flanges E⁸, formed at the lower end of the upper section 50 E² of the pair. A gland E⁹ is provided for compressing the packing, and is operatively connected with the casting by bolts E¹⁰. Ears E¹¹ are formed on the casting E⁴ for the pivotal connection of straps E¹², which extend 55 from the casting E⁴ to a clamping-band E¹³, which embraces the upper section of a pair.

E¹⁴ represents the pivots or bolts passing through the ears E¹¹ and through the straps 60 E¹². The upper ends of the straps are secured to the clamping-band by bolts E¹⁵, which may be provided with a lever or hand-wheel E¹⁶, whereby the clamping-band may be brought snugly against and around the upper section 65 of a pair to maintain it in any desired position—primarily, an extended position with relation to an adjacent section, and, second-

arily, in a retracted position within an adjacent lower section. When the stand-pipe is in a vertical position with the sections thereof closed telescopically, all of the clamping-bands E¹³ and levers or hand-wheels E¹⁶ are in a position accessible from the platform C¹⁰, so that an operator upon said platform may successively loosen the clamping-bands of the 70 sections, beginning with the upper, and thus permit the same to be extended by the pressure of water let into the stand-pipe in a manner hereinafter described. The clamping-bands also serve the purpose of securing the 75 sections at any point between the ends thereof, as when desirous of extending the stand-pipe to less than its full height. The casting E⁴, which serves the function of a coupling between the sections, is also provided with 80 diametrically-opposite pairs of lugs E¹⁷, provided at their extremities with vertical tubular bearings for supporting a series of telescoping tubes coextensible with the sections of the stand-pipe proper and connected so as 85 to communicate a rotary motion from one tube to the other of the series for the purpose of controlling the nozzle and co-operating devices arranged at the top of the stand-pipe. The purpose of the spring E⁷, arranged 90 between the inner annular flange of the coupling or casting E⁴ and the external flange E⁸ of the upper section of a pair, is to cushion the same against undue concussion of these flanges when extending the stand-pipe. The 95 butt or lower end of the stand-pipe is closed by a casting, cap, or cup F, interiorly screw-threaded, as at F', for connection with the section. A port F² communicates with the interior and the cap is extended laterally, as 100 at F³, and terminates in a flange F⁴, through which bolts F⁵ are passed for the purpose of securing to the face of the flange a casing F⁶, adapted for the connection of hose thereto and for the operation of valves therein. 105

Two openings F⁷ are provided, one upon each side of the central port F², and these openings F⁷ pass through the walls of the cap, so as to serve as ways for check-valves 110 employed in connection with the supply-ports of the stand-pipe. One of the check-valves is shown in Fig. 30, it being understood that it is one of a pair, the other being arranged on the opposite side of the central port F². In the opening F⁷ there is a bushing F⁸, and in the bushing there is a slide or check valve F⁹, which comprises a cylinder (see Fig. 33) one end of which has an internal spider or lugs F¹⁰, and the opposite end of which is screw-threaded internally, as at F¹¹, for the 115 reception of the valve-head F¹². (See Figs. 33 to 36, inclusive.) The valve-head has a wrench-hold F¹³ in its face, whereby the same may be inserted and removed from the cylinder. The object of the lugs or spider is to 120 form a bearing for a removable nut or collar F¹⁴ on the rod F¹⁵, seated in a projection or lug F¹⁶ on the inner wall of the cut F at a point opposite the opening F⁷. A coiled 125

spring F¹⁷ encircles the rod F¹⁵, and its tension is regulated by a movable collar F¹⁸, mounted on the rod and held in any desired position thereon by means of a set-screw F¹⁹.

5 F²⁰ represents the seat for the valve F⁹, and it is arranged in the passage formed in the casing F⁶, which terminates in a bib F²¹, adapted to operatively receive the coupling of any ordinary hose F²².

10 The port F² is opened and closed by means of a slide valve or gate F²³, from which a rod F²⁴ passes upwardly and along the lower section of the stand-pipe to a point above the platform C¹⁰, where by means of suitable gearing inclosed in a case F²⁵ and a suitable hand-wheel F²⁶, projecting from said case, the desired operations of the slide valve or gate may be accomplished. In addition to the bibs F²¹, the casing F⁶ is also provided with a discharge 15 port or passage F²⁷. A stuffing-box F²⁸ is provided for the slide-valve rod F²⁴.

The object and purpose of the check-valve F⁹ at the base of the stand-pipe are to prevent an unintentional descent of the sections of the 20 stand-pipe by reason of a cutting-off or a material lessening of the pressure of water for supplying the pipe. In case the pressure is materially lessened—for example, by the bursting of the hose—the check-valve F⁹, which, having been adjusted to yield to a normal pressure of incoming water, so as to be forced back to substantially the position shown in full lines in Fig. 30, will, by means of the pressure of the spring, be carried forward into its seat F²⁰, as shown in dotted lines in said figure, and thus prevent the escape of the column of water within the stand-pipe, and so prevent the collapsing or closing telescopically of the sections thereof. The check-valves F⁹, therefore, will automatically enter their seats F²⁰, and the slide valve or gate F²³, being in its upper position, as shown in Fig. 31, will close the discharge-passage F²⁷. Now by lowering the slide valve or gate (which is shown in 25 front and end elevations, respectively, in Figs. 28 and 29) to the position shown in Fig. 32 the column of water within the stand-pipe may be gradually discharged therefrom through the passage F²⁷. It is also apparent that the 30 slide valve or gate may be arranged in a position to close both the port F² and the discharge-passage F²⁷, so that the column of water is retained within the stand-pipe, and in connection with the check-valves F⁹, seated at F²⁰, the disconnection of the hose or a breakage 35 thereof may occur without the collapsing of the pipe.

An important feature of construction at this portion of the apparatus is the provision of a casing having within itself valve-seats and valves necessarily employed at the butt of the stand-pipe, so that by simply removing the casing and without the necessity of removing the cap from the lower section 40 of the stand-pipe all these parts are accessible for cleaning, repairing, and other purposes. The upper end of the section E³ of

the stand-pipe terminates in a casting (shown in plan in Fig. 23 and section, Fig. 17) internally screw-threaded for connection with the pipe E⁸. In this casting is formed the cylindric chamber H, the walls of which are represented by H'. From the exterior of this chamber project radially two diametrically-opposite lugs H², provided at their extremities with vertical tubular bearings H³, like E¹⁷, and with the same function. The cylindric chamber H serves as a socket in which the rotatable pipe I is fitted to rotate. The lower extremity of pipe I is expanded, forming the hollow cylinder I³, which is fitted to rotate in the socket or chamber H. The expanded portion I³ of the pipe I is retained within the socket H by means of the retaining ring or cap H⁴, secured to H by screws or other suitable means.

Within the cylinder I³, with coincident axis, is the hollow cylinder I⁴, exteriorly provided with radial longitudinal flanges I⁶, extending to and by any convenient means secured to the walls of I³, by which means the cylinder I⁴ is maintained in position. The lower end of cylinder I⁴ is closed in this instance by the cap I⁵. The several concentric cylindric members H, I³, and I⁴ are so relatively proportioned as to afford an ample passage for water to flow freely upward from the section E³ around and past the cylinder I⁴ into the rotatable pipe I.

Within the cylinder I⁴ is fitted the cylindric slide-valve I⁷, which may be raised until, being seated against the shoulder I², it shall cut off the exit of water through the pipe I, in order to utilize the pressure of the water for extending the stand-pipe. The valve I⁷ is actuated through the valve-rod I⁸, located in the interior of the rotatable pipe I and suitably secured to the valve in this instance by being connected with the spider I⁹. The pipe I is pierced by one or more (in this instance two) longitudinal slots I', as long as the required travel of the valve and opposite the upper extremity of the valve-rod I⁸. From the upper extremity of the valve-rod I⁸ project laterally one or more (in this instance two) lugs I¹⁰, which project through the slots or slot I' somewhat beyond the exterior surface of the pipe I. Surrounding the pipe I and covering the slot or slots I' is fitted a longitudinal movable sleeve P. Any inconvenient escape of water from the slots I' is prevented by the close fitting of the sleeve P to the outer surface of the pipe I, or, as in this instance, by the stuffing-boxes O at the ends of the sleeve P.

The inner surface of the sleeve P is provided with an annular groove P', which engages the lug or lugs I¹⁰. In this instance the annular groove P' is formed as follows: The part of the sleeve P above the groove fits closely to the outer surface of the pipe I. The part below the groove is interiorly of greater diameter than the pipe I, and the space intervening between P and I is filled by an

intermediate sleeve P^2 , held in place by the packing and gland of the lower stuffing-box O , the upper end of the intermediate sleeve forming the lower margin of the groove. It is manifest that when the sleeve P is made to move longitudinally on the pipe I the engagement of the groove P' with the lug or lugs I^{10} will impart a corresponding motion to the valve I^7 through the valve-rod I^8 without interfering with the free rotary motion of the pipe I . The sleeve P is provided exteriorly with a lug or lugs P^3 , one or more of which lugs are provided at their extremities with a screw P^4 , axially parallel to the sleeve P . The screw P^4 engages with a screw N' of opposite sex. The screw N' is either attached to the upper end of the rotatable shaft N , (to be described hereinafter,) with common axis therewith, as in this instance, or may be parallel therewith and geared thereto. Rotary motion imparted to the shaft N , actuating the screw N' , will raise or lower the sleeve P . In the present instance one of the lugs P^3 terminates in a tubular bearing P^5 , axially parallel to the sleeve P , which bearing is fitted for longitudinal motion to the spindle M' , attached to the upper end of the rotatable shaft M , (to be described hereinafter.) By this means additional support and steadiness is afforded to the sleeve P .

The discharge-pipe K is connected with the upper end of the rotatable pipe I in the present instance by the flexible hose K' , though the connection may be made through any suitable flexible joint.

The sleeve P is provided exteriorly and in a plane at a right angle with the axis with a circular or partly-circular guide concentric with the sleeve P , which in this instance is the groove P' . Fitted to this guide so as to freely traverse the same is the traveler U , which in this instance is a ring fitting the groove P' , made in halves and held together by screws or bolts passing through suitable ears on the two halves. Firmly secured to this traveler by any suitable means is the spindle Q , axially parallel to the pipe I . In this instance the lower end of the spindle is reduced in diameter and passes through a lug formed on the traveler U , and is firmly held there by the nut Q' . The parallelism of the spindle Q with the pipe I is rigidly maintained by means of the tubular guide Q^2 , in which the spindle Q is fitted to move longitudinally, the guide Q^2 being rigidly secured to the upper end of the pipe I by any suitable means, in the present instance by the collar R , Fig. 17^a, made in halves and bolted together, so as to embrace both the pipe I (which, in addition, is screw-threaded into it) and the tubular guide Q^2 .

To the upper end of the spindle Q is hinged or pivotally connected the connecting-rod or pair of rods R^5 , the upper end or ends of which rod or rods having pivotal connection with the discharge-pipe or an attachment thereof. When longitudinal motion is imparted through

the sleeve P and traveler U to the spindle Q and connecting-rod or pair of rods R^5 , the nozzle of the discharge-pipe K is elevated or depressed, while at the same time, owing to the traveler U freely traversing the guide P' , the rotary movement of the pipe I and its attachments is not impeded. In the present instance, where the discharge-pipe K is connected with the rotatable pipe I by flexible hose, the flexion of the hose is confined to the common plane of the axis of the pipe I and spindle Q , and the connection of the rod or rods R^5 with the discharge-pipe is effected by the following mechanism: From diametrically-opposite points on the collar R and in a plane at a right angle with the desired plane of flexion of the hose arise vertically two rigidly-fixed stanchions R' , with sufficient clearance between them for the hose. These stanchions are pivotally connected at their ends with the ends of another similar pair R^3 , proceeding from diametrically-opposite points in a sleeve or runner R^4 , which is fitted to slide loosely on the outer surface of the discharge-pipe K . To this pair of stanchions R^3 the pair of connecting-rods R^5 (or single rod bifurcated at its upper end) are pivotally connected, as shown in Fig. 17^a.

To the upper end of the shaft M , above the bearing H^3 , is rigidly secured by a key or other suitable means a gear-wheel L^2 , which engages with a gear-wheel L , which is rigidly secured by a key or other suitable means to the rotatable pipe I , whereby rotary motion imparted to the shaft M is communicated to the pipe I .

In Fig. 1 and in Figs. 42 to 45, inclusive, are illustrated a gear-cap employed in connection with the gears L to L^2 . The gear L has an annular groove L^3 in its rim for the purpose of sustaining and permitting the operation of friction-rollers L^4 , which are mounted on studs or bolts L^5 , passing through the gear-cap L^6 , which has an opening L^7 for the passage therethrough of the section of the stand-pipe and an opening L^8 for the passage therethrough of the tube or rod M , which operates the pinion L^2 . There are three friction-rollers the bolts of which pass through the apertures L^9 of the cap, whereby the rollers are rotatively secured to the cap, so that these pulleys serve to support the cap over both of the gears in such a manner as not to impede the rising and falling or rotative movements of the upper section I , yoke J , and its appendages. The rods or tubes M and N pass along the stand-pipe, one at each side thereof, and through vertical tubular bearings in the lugs E^{17} , which are formed on the various yokes employed. These rods or tubes are made in sections agreeing and coinciding with the stand-pipe proper, the upper section being, if desired, in the form of solid rods, while the remaining sections at each side are in the form of tubes or hollow bars or rods; (see Fig. 40,) each having a spline M' , fitting a groove in the inner portion of the next adjacent sec-

tion, so that the sections are capable of longitudinal movement independent of each other, but communicate a rotary movement given to the lower section to each and all of the sections above it. The duties performed by the rods at their upper ends have been stated.

At the joints of the stand-pipe and in the lugs E^1 a lower rod of a pair passes through a sleeve M^2 , which is secured to the rod by a pin or bolt M^3 , and which has a collar adapted to fit the under surface of the lug E^1 . This sleeve passes upwardly through the lug, as shown by dotted lines, Fig. 19, and has attached to its upper end a collar M^4 . The sleeve and its collars prevent longitudinal movement of the tube M and permit a rotary movement thereof. The tube M may extend completely through the sleeve and flush with the upper surface of its upper collar and be secured at that point by the pin M^5 , which serves to secure the collar to the sleeve. The next section above the tube M , having the spline M' , may pass through the lug E^1 at the next section above of the stand-pipe and be connected therewith in a like manner, whereby each section of the telescopic tube is operated in a similar manner as the stand-pipe proper and by the same means. A preferred construction is shown in Fig. 19^a, in which construction each pipe has a cast head or sleeve M^{2x} , and the groove M^{3x} is in the head or sleeve only, in which the spline in the next section rides.

Referring now to Figs. 37 to 41, inclusive, it will be seen that a miter-gear S is affixed to the outer tube M of the series and meshes with a miter pinion-gear S^1 , mounted on the shaft S^2 , which is provided with a hand-wheel S^3 . The gears and shaft are mounted in a gear-case T , secured to the stand-pipe at a point accessible from the platform thereof, as clearly shown in Fig. 2. Each of the cases is formed of two parts $T T'$, the latter forming the cover and constructed to give space internally for one-half of the gear and to provide one-half of the bearing for the gear S and shaft S^2 , the parts being secured together by bolts passing through perforated bosses F^2 , and the case being provided with apertured lugs T^3 , through which bolts are passed to clamp the same to the stand-pipe.

An inspection of Figs. 37 to 41 will show that each of the cases is adapted to conform to the gearing and tubes therein and passing therethrough and to the lower section of the stand-pipe, Fig. 37 being a side elevation of the cover; Fig. 38, a plan of the case with the cover removed, the tubes and gearing being in position; Fig. 39, a side elevation or edge view of the case; Fig. 40, a plan, the tubes being shown in section and the gear S in plan; and Fig. 41, an end elevation looking toward the bearing of the gear-shaft S^2 , the cap and case being in operative position.

The object and purpose of the gear-case, to-

gether with the gear-cap L^6 , are to protect the gearing from ice when using the apparatus in cold weather.

What we claim is—

1. In a stand-pipe, the combination, with a valve of any suitable construction located in the path of water therethrough, the main conduit, and the rotatable pipe attached to the outlet of such conduit and provided with a rod for opening or closing said valve, such rod being arranged in the direction of the axial line of the conduit and having at its upper extremity one or more projecting lugs passing through a longitudinal slot or slots in such rotatable pipe, each slot being as long as the required travel of the valve-rod, of a longitudinally-movable sleeve surrounding said rotatable pipe and provided with an internally-annular groove to engage the ends of the lugs projecting from the valve-rod, so that a longitudinal motion of the sleeve shall be imparted to the valve-rod, while the rotary movement of the pipe is not impeded, said sleeve being adapted to prevent any inconvenient escape of water through the slots in the rotatable pipe by means of good fitting or of stuffing-boxes at each end of said sleeve, a non-rotatable screw attached to said sleeve axially parallel thereto and adapted to fit and be actuated by a rotatable screw of opposite sex, whereby said sleeve may be elevated or depressed, a rotatable shaft axially parallel to said sleeve and supported in suitable bearings, and a rotatable screw operatively connected with said rotatable shaft and adapted to engage with the screw attached to the aforementioned sleeve, whereby the rotation of the shaft shall elevate or depress the valve-rod and open or close the valve, substantially as specified.

2. The combination, in a stand-pipe, of, first, a pipe having a common axial line with the main conduit and so connected with the upper end of such conduit as to be freely rotatable around its axial line; second, a discharge-pipe so connected with the upper end of said rotatable pipe by a suitable flexible joint that the axial line of said discharge-pipe may be adjusted at any angle with the axial line of said rotatable pipe; third, a guide arranged around said rotatable pipe concentric therewith, but not attached thereto, in a plane at a right angle with the axial line of the rotatable pipe, adapted to receive and be traversed by a suitably-formed traveler properly fitted thereto, said guide having attached to itself and being supported by a non-rotatable screw with the axis or axes parallel to axis of the rotatable pipe adapted to fit and be actuated by another rotatable screw of opposite sex, whereby said rigid guide may be elevated or depressed; fourth, a traveler of suitable form and adjusted to traverse freely said guide; fifth, a rigid link or links connecting said traveler to the discharge-pipe by suitable flexible joints, so that

- the elevation or depression of the guide and traveler shall elevate or depress the nozzle of the discharge-pipe; sixth, a rotatable shaft with axis parallel to the axial line of the main conduit and supported in suitable bearings, and, seventh, a rotatable screw operatively connected with said rotatable shaft and with the aforementioned guide, whereby rotation of the shaft shall elevate or depress the guide.
10. 3. The combination, in a stand - pipe, of, first, a slide-valve seated on the inner surface of the wall of said stand-pipe near the lower end thereof, said valve being provided with any suitable device whereby it may be actuated from without; second, an induction-port piercing the wall on which the valve is seated within the area of such seat and communicating with an outer water-tight chamber; third, an eduction-port piercing the wall on which the valve is seated within the area of such seat and communicating with the external atmosphere; fourth, an outer water-tight chamber communicating with the interior of the main conduit through the above-mentioned induction-port and having one or more external openings for admission of water; fifth, one or more external openings in the wall of the outer chamber for admission of water, each opening being provided externally with means for attaching the hose thereto and internally with a check-valve to prevent egress of water therethrough, the induction and eduction ports being arranged relatively to each other in the direction of the travel of the slide-valve, the slide-valve being of sufficient area to cover both ports and so limited in its travel that a movement of the valve in either direction from its position covering both ports shall open only the port from which the valve is being moved, all substantially as and for the purpose specified.
4. In a truck, a side rail composed of channel-irons and plates connected to form grooves extending from the end toward the middle of each sill, substantially as described.
5. In a truck, a side rail composed of channel-irons and plates connected to form grooves extending from the end toward the middle of the sill and at substantially the center shaped to form pockets A⁶ for the reception of the stand-pipe-elevating cylinders, substantially as described.
6. In a truck, a side rail composed of channel-irons and plates connected to form grooves, as described, and with pockets for the reception of the stand-pipe-elevating cylinders, and one of said irons bent downwardly, as at A³, for the reception of a foot of a brace, substantially as and for the purpose specified.
60. 7. The combination, with a stand-pipe-supporting cylinder, of a side rail or sill formed of channel-irons and plates, the latter secured to the edges of the channel-irons and having a pocket for the cylinder and stay or truss rods and extending from the cylinder to the side rail or sill, substantially as specified.
65. 8. In a stand-pipe truck, a side rail or sill

having a brace-receiving depression or recess, a stand-pipe, and a brace adapted to co-operate with the stand-pipe and with the rail or sill, substantially as specified.

9. The combination of a stand-pipe-supporting cylinder, a rail or sill formed of channel-irons and of plates curved to embrace the cylinder, and stay or truss rods extending from opposite ends of the cylinder to the rail or sill, substantially as specified.

10. The combination of a telescopic cylinder for supporting a stand-pipe with a rail or sill having a groove in its upper edge, a brace pivoted to the movable section of the cylinder and having its lower end adapted to slide in the groove of the rail or sill, and a recess or depression in the bottom of the groove for retaining the brace in a desired position when the removable section is extended, substantially as specified.

11. In a stand-pipe truck, a rail or sill formed of channel-irons and plates, adapted to embrace the stand-pipe-supporting cylinder, and provided with a groove in its upper edge and having a recess therein, in combination with said cylinder, a brace pivoted thereto, and a bar for closing the recess, substantially as specified.

12. In a stand-pipe truck, a stand-pipe support, a brace for the same, a side rail or sill having a groove in its upper edge provided with a brace-receiving recess and having a bar for closing the said recess, substantially as specified.

13. A stand-pipe-supporting telescopic cylinder provided with pivoted braces, in combination with a rail or sill having recesses for receiving the braces and bars and racks and pinions for forcing the same into the recess for closing the same, substantially as specified.

14. In a stand-pipe truck, the combination, with the telescopic cylinders and with braces pivoted to the cylinders and bearing upon the truck, of stay-rods secured at their upper ends to the braces and connected at their lower ends to a sliding block, and a rod for reciprocation between steps or collars arranged in the path of the block and on which said block slides, substantially as specified.

15. A stand-pipe truck having a platform cut away at the forward end thereof, with vertical telescopic cylinders for supporting the stand-pipe by means of a joint fastened above the center of gravity of said pipe, a pipe curved rearwardly connecting said cylinders, and devices for the attachment of hose fixed to said pipe, substantially as described.

16. The combination, with the stand-pipe and its supporting - cylinders and with the cylinder-connecting curved pipe, of guy-bolts connected with the said pipe and detachably with the stand-pipe, substantially as specified.

17. The combination, with telescopic cylinders for supporting a stand-pipe, of a truck carrying the cylinders and of braces pivot-

ally connected with the telescopic section of the cylinders, one or more of which braces are in the form of a ladder, and sliding pivotal braces connecting said ladders with one of the cylinders, substantially as specified.

18. The combination, with a telescopic stand-pipe and with telescopic cylinders for supporting the same, of a brace pivoted at one end to opposite cylinders and comprising a cross-bar arranged near the pivoted end of the brace, whereby the same is strengthened and adapted to bestride the stand-pipe when in a horizontal position, substantially as specified.

19. In a stand-pipe, and in combination with the curved cross-beams, the platform having open portion, and the stand-pipe-supporting cylinders, a system of pivotally-connected braces consisting of a number of separate braces and a single brace constructed to bestride the stand-pipe, substantially as specified.

20. In a stand-pipe truck, the extensible stand-pipe, supports having braces, side rails or sills having grooves in their upper edges for receiving said braces, the feet of which are adapted to slide in said grooves, recesses for receiving the feet of the braces, bars arranged to enter the recesses for closing the same, rack-bars for operating the recess-closing bars, and a cross-shaft having pinions for operating the rack-bars, substantially as specified.

21. In a stand-pipe truck having a framework the forward part of which is open and which is provided at about its mid-length with stand-pipe-supporting cylinders connected at their lower ends by a rearwardly-curved pipe and at their upper ends by a forwardly-curved beam, a stand-pipe pivotally suspended above its center of gravity from said beam and the trussed pivoted braces, and a stand-pipe retaining or locking device arranged at the front end of the truck, whereby the stand-pipe may be supported and maintained in a horizontal position upon the truck and at will without the use of extraneous means changed to a vertical position upon the truck, substantially as specified.

22. In a telescopic stand-pipe having section-securing devices, the combination, with a valve at its lower end for admitting and discharging and cutting off the supply of water, and a rod operating said valve extending upwardly along the stand-pipe and terminating with gearing for operating the rod, of a platform secured to the stand-pipe, the platform being arranged to give access to the said rod and to the section-securing devices of the stand-pipe, whereby a single attendant can control the operation of extending and retracting the stand-pipe, substantially as specified.

23. In a stand-pipe, supply-ports and automatic valves for closing the same and an intermediate discharge-port, all communicating with the lower section of the pipe, the said

valves being adjusted to yield to the normal pressure of the incoming water, substantially as described.

24. In a stand-pipe, and in combination with a lower section thereof, supply-ports, spring-actuated automatic plugs or check-valves for closing the same, and intermediate discharge-port and a valve or gate for opening and closing the same at will, all arranged at and having direct communication with the lower end of the lower section of the stand-pipe, substantially as specified.

25. The combination, with a stand-pipe and with a lower section thereof, of a casing adapted to close the end of said section, provided at its side with a supply-port formed with a valve-seat and with means for connection of a hose, a check plug or valve, and means for yieldingly holding the same in the valve-seat, substantially as specified.

26. In a stand-pipe, and in combination with a lower section thereof, a casing adapted to close the end of said section, provided with a supply-port, a valve yieldingly closing the same, a discharge-port, and a sliding gate for closing the same, substantially as specified.

27. In a stand-pipe, a separable casting adapted to close the end of a lower section and provided with supply-ports, check plugs or valves for closing the same, a discharge-port, and a sliding gate or valve for the same, substantially as specified.

28. In combination with a stand-pipe, a guy-bolt having an enlarged head and an adjacent contracted neck, a cylinder connected with the stand-pipe and having an opening for receiving the head, an inner cylinder provided with an operating-stem and slotted to embrace the neck of the bolt, and upper and lower seats for securing the head of the bolt against vertical movement, substantially as specified.

29. A coupling for the telescopic sections of a stand-pipe, interiorly screw-threaded for connection with a section, provided with an annular internal flange, opposite lugs E¹⁷, and with diametrically-opposite ears E¹¹, substantially as specified.

30. The combination, with two adjacent sections of a telescopic stand-pipe, of a coupling having an internal annular flange, exterior diametrically-disposed ears, a gland and a clamp, means for tightening the same, and clamp and coupling connecting links, substantially as specified.

31. The combination, with the several sections of a telescopic stand-pipe and with the nozzle of its terminal section, of a series of telescopic tubes, and a rod connecting the upper tube with the nozzle, and bearings at the joints of the sections for supporting and guiding the telescopic tube, substantially as described.

32. In combination with the nozzle of a telescopic stand-pipe, a flexible hose-section contained within frames which are connected with the nozzle, the upper section of the stand-pipe, and with each other, and with an arm

extending from one of the frames to a rod which is connected to the telescopic nozzle-controlling pipes by an intermediate sleeve mounted for longitudinal reciprocation upon 5 the stand-pipe, substantially as specified.

33. In a stand-pipe, and in combination with an upper section thereof, a cut-off, a sliding sleeve connected therewith, and a series of telescopic tubes connected with and for operating the sleeve, substantially as specified.

34. In a stand-pipe, and in combination with an upper section thereof, a flexible nozzle, a sliding sleeve connected therewith, and a series of telescopic tubes connected with and for operating the sleeve, substantially as specified.

35. In a stand-pipe, and in combination with an upper section thereof, a flexible nozzle and a cut-off, a sleeve connected with both, 20 and a series of telescopic tubes connected with and for operating the sleeve, substantially as specified.

36. In a stand-pipe, the combination, with a rotatable upper section terminating in a 25 flexible section, of hose, a sliding sleeve operatively connected with said hose, a system of gearing, and two series of telescopic tubes for operating the yoke and gearing, substantially as specified.

37. In a stand-pipe, an upper rotatable section, a system of gearing connected therewith, a sleeve and a cut-off connected therewith, a yoke connected with the sleeve, and two series of telescopic tubes connected with 35 the yoke for operating the sleeve and gearing, substantially as specified.

38. In a stand-pipe, telescopic pipes and a cut-off valve arranged in an upper section, a yoke movable on the telescopic pipes, telescopic tubes, and connecting devices between the valve and the yoke operated by said telescopic tubes, substantially as described.

39. A cut-off valve comprising a cylinder of less diameter than the section in which it is located, provided with ports and a valve 45 for closing the ports, a sleeve embracing the section, a yoke connected with the sleeve, and connections between the sleeve and a series of telescopic pipes for operating the valve and 50 accessible from the platform of the stand-pipe, substantially as specified.

40. In a stand-pipe, and in combination with an upper section thereof, cut-off mechanism, a sliding yoke, devices for connecting the cut-

off mechanism therewith, and nozzle-deflecting mechanism connected with the yoke, and a series of telescopic pipes connected with and extending from the yoke along the stand-pipe to a point accessible from the platform thereof, substantially as specified.

41. In combination with a rotatable section of a stand-pipe, a gear fixed to the section and provided with an annular groove and a cap provided with frictional rollers arranged in the groove, whereby the cap is supported by 60 the gear, substantially as specified.

42. A gear-cap provided with friction-rollers located inside of the cap, in combination with a gear, the rollers having a bearing upon the gear and serving to support the cap, substantially as specified.

43. A gear-cap provided with openings for a stand-pipe section and for a controlling-pipe, and conforming to the gear for covering the same, and provided with friction-rollers 75 having cap-supporting contact with the gear, substantially as specified.

44. The exterior detachable casing for the operating-gear of a stand-pipe, having opposite bearings for the nozzle-controlling tubes 80 and for a pinion secured to one of the same, and having a bearing for a shaft of a companion gear and a base adapted for attachment to a section of the stand-pipe, substantially as specified.

45. The combination, with a section of the stand-pipe and with the nozzle-controlling gearing thereof, of removable gear-casing conforming to the stand-pipe and adapted to be clamped to the same, substantially as 85 specified.

46. The combination, with the nozzle-operating device of a stand-pipe, of a divided casing adapted to be secured to a section of the stand-pipe and having bearings for the nozzle-operating devices therein and passing therethrough, and means for securing the separable parts of the casing to each other, whereby ready access may be had to the nozzle-operating devices within the case, substantially as specified.

In testimony whereof we affix our signatures in presence of two witnesses.
